UNITED STATES PATENT OFFICE

2,561,435

ECONOMICAL UMBRELLA FRAME
STRUCTUREVan Lear Woodward, Staten Island, N. Y., assign-
or to Van Lear Woodward & Co., Inc., New
York, N. Y., a corporation of Delaware

Application November 30, 1949, Serial No. 130,100

2 Claims. (Cl. 135—20)

1

The present invention relates to umbrella frame structures of the type primarily designed for economy in construction and materials; and has for a general object provision of such frame structure which can be and preferably is formed of relatively cheap materials, such as wood, paper and cord, by simple and economical operations in mass production with the use of unskilled labor, such umbrellas being effectively waterproofed efficiently to protect a user from moisture or rain and primarily designed for a one-use purpose, the umbrellas being marketable at a price permitting discard after being used once, although the structure is of such durability as to permit repeated use.

A more specific object of the present invention is to provide in such economical umbrellas frame structure characterized by construction of the ribs and stretcher arms from strips of wood and the tip head and stick runner from shaped and cut pieces of wood held together in an effective fashion by cords, such as textile strings, the rib and stretcher arm joints being provided in a simple manner by splitting of ends of the arms to form forks, each comprising a pair of resilient prongs snugly to engage opposite sides of an apertured portion of a rib, with substantially aligned apertures in the prongs and the rib frictionally receiving therethrough a portion of a continuous loop of cord to form an effective hinge joint.

A further object of the present invention is to provide a structural embodiment of the device which may be readily constructed and permits efficient use and operation thereof.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had to the following detailed description taken in connection with the accompanying drawing, in which:

Fig. 1 is a perspective view from the underside of an embodiment of the umbrella of the present invention in opened position;

Fig. 2 is an enlarged detailed perspective view, with parts broken away, of the rib and stretcher arm joint structure of the construction shown in Fig. 1, and showing details of associated elements;

2

Fig. 3 is an enlarged sectional view, with parts broken away, taken substantially on line 3—3 of Fig. 2;

Fig. 4 is an enlarged sectional view, with parts broken away, of the umbrella structure shown in Figs. 1, 2 and 3, showing the stick in elevation and the tip head and runner in axial section;

Fig. 5 is a sectional view, with parts broken away, taken substantially on line 5—5 of Fig. 4, showing a top plan view of the runner and the ends of the stretcher arms pivoted thereto;

Fig. 6 is an enlarged perspective view of the runner; and

Fig. 7 is a side elevational view, with parts broken away, of the umbrella construction shown in Figs. 1 to 6, inclusive, indicating relative positions of parts when the umbrella is partially open or being manipulated to closed position.

Referring to the drawing, wherein like numerals identify similar parts throughout, it will be seen that the preferred embodiment of the invention disclosed therein comprises a stick 10, a stick runner 11, tip head 12, ribs 13—13, cover 14, and stretcher arms 15—15. In an economical embodiment, the stick 10 comprises a length of bamboo, the runner 11 comprises a wooden sleeve, the tip head 12 comprises a wooden cap or socket, and the ribs 13—13 and stretcher arms 15—15 preferably are formed of strips of bamboo.

As will best be seen from Fig. 4, the tip head 12 preferably is a substantially cylindrical body provided with an axial socket 16 in which is received the top end 17 of stick 10. The lower portion of the tip head 12 has radial slots 18—18 cut or sawed therein, preferably through to the socket 16 to define a circle of rib-separating segments 19—19, each slot receiving an end 20 of one of the ribs 13. The outer cylindrical surface 21 of the slotted lower portion of the tip head 12 is provided with a discontinuous or interrupted circular groove 22, each section of which traverses the outer face of one of the segments 19. The end 20 of each of the ribs 13 has an aperture therein. A cord or string 23 is threaded through those rib apertures, seated in the sections of the interrupted groove 22 and tied tightly in its encircling position pivotally to mount to the tip head 12 the ends 20—20 of the ribs 13—13.

To the upper edges 24—24 of the ribs 13—13 is cemented or glued a webbing of waterproofed paper, or its equivalent, to provide the cover 14. In order to assure complete protection from rain to the user, the wooden tip head 12 preferably is covered by a layer 25 of waterproofed paper, or its equivalent, and, as shown in Fig. 4, the

skirt of the resulting cap for the tip head is lapped over and cemented to the inner edge of the webbing of cover material 14 to provide a water-proofed joint. The outer ends 25—26 of the ribs 13—13 are preferably connected together by a loop of cord or string, with the edges of the cover 14 in each segment intervening a successive pair of ribs 13, 13 lapped back thereabout and cemented to the main portion of the cover to form an edge seam, as indicated at 27—27.

As shown in Figs. 1, 2 and 3, each rib 13 is provided, intermediate its inner and outer ends 20 and 26, with a joint structure 28 comprising an enlargement or ear 29 disposed on or made integral with the bottom edge of the rib. Each projection or ear 29 is pierced or provided with a through aperture or hole 30 of certain diameter. Outer end 31 of each stretcher arm 15 is split, as best shown in Fig. 3, to provide a fork comprising a pair of resilient prongs 32, 32, which are stressed when separated snugly to receive therebetween projection or ear 29. In fact, there is appreciable frictional engagement between the inner faces of the prongs 32, 32 and the outer sides of the projection or ear 29 since there is a tendency for the prongs to snap together. Each prong 32 has its end pierced or provided with a hole or aperture 33 of a diameter substantially equal to the hole or aperture 30 in the ear or projection 29. A continuous loop of cord or string 34, provided by a length thereof having its ends tied together, such as at 35 in Fig. 1, is strung successively through the aligned apertures 33, 30, 33 in the successive joints joints 28—28.

As best shown in Fig. 1, each length of the continuous loop of cord 34 between successive joints 28, 28 is substantially equal to the width of the segment of webbing 14 at the joints so that when the umbrella is opened to the protective position indicated in Fig. 1, the various sections of the cord 34 are drawn tautly between the successive joints 28—28. The cord or string 34 is preferably made from textile fibers and is of a rather compact nature, being treated or waxed if desired, so as to require a fair amount of squeeze force to reduce it in diameter at any particular point. Further, it is of a diameter substantially greater than the diameters of the holes 30—30 and 33—33 so that in order to pull it therethrough a fair amount of tension must be applied in stringing the parts together. As a result, the rib and stretcher arm parts at the joints 28—28 will be held effectively together both by the resilient gripping of the projections or ears 29—29 between the pairs of resilient prongs 32—32 and by the frictional mounting of the cord through those smaller apertures. Thus, when the umbrella is collapsed, the various lengths of the cord 34 intervening the successive joints 28—28 will fall loosely to the positions indicated in Fig. 7 and will remain substantially equal in length so as to avoid interfering with the opening action.

As best seen in Figs. 4, 5 and 6, the stick runner 11 is preferably made as a substantially cylindrical wooden sleeve having a round axial bore 36 of a diameter at least slightly larger than the diameter of stick 10 so as slidably to receive the latter freely therethrough. The upper portion of the stick runner 11 is provided with a plurality of radial slots 37—37 cut or sawed therein, preferably to the bore 36, so as to define therebetween a circle of stretcher arm-separating segments 38—38. The cylindrical outer sur-

face of the upper portion of runner 11 is provided with a discontinuous or interrupted circular groove 39 so that sections thereof traverse the outer faces of the segments 38—38 as best seen from Fig. 6.

Each stretcher arm 15 has a bottom end 40 pierced or provided with a transverse aperture or hole 41, through which a length of string or cord 42 is strung, with the stretcher arms ends 40—40 located in the slots 37—37, as indicated in Fig. 5. The cord 42 is seated in the interrupted groove 39 and tightly tied in position, such as at 43, as clearly shown in Fig. 5, pivotally to anchor the bottom ends of the stretcher arms to the stick runner 11.

As is indicated in Figs. 1 and 4, the stick 10 is preferably provided with a pin 44 extending through a transverse hole therein to provide an upper stop for the runner 11 and also with a spring tongue 45 to form a latch for holding the umbrella in its open position in the manner indicated in Fig. 4.

It will thus be seen that the umbrella structure illustrated in the drawing is of very economical construction and, incidentally, it is intended primarily for emergency use. Its construction makes possible its sale at an unusually low price so that when an unexpected rain storm appears, one may purchase one of these umbrellas at a nearby newsstand or variety shop. Its use in the emergency may avoid a wetting necessitating an expensive cleaning and/or pressing of a person's cloths. The umbrella construction may also be useful to courteous hosts for presentation to their guests in emergencies.

It will thus be seen that the objects set forth above, among those made apparent from the preceding description are efficiently attained and, since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. Frame structure for an economical umbrella comprising, in combination, a stick fitted with an enlarged circular wooden tip head having radial slots cut in the bottom portion thereof defining a circle of separating segments each having a transverse groove cut into its outer face aligned with those in the other segments, a plurality of wooden ribs each having an apertured end disposed in one of said slots, an anchoring cord strung through the apertures in said rib ends and tied tightly in said aligned grooves, a substantially cylindrical wooden runner having a bore slidably receiving said stick and having radial slots cut in the top portion thereof defining a circle of separating segments each having a transverse groove cut into its outer face aligned with those in the other segments, a plurality of wooden stretcher arms each having an apertured end disposed in one of said runner slots, an anchoring cord strung through the apertures in said stretcher arms and tied tightly in said runner grooves, each of said stretcher arms having its other end split to form a fork between the prongs

of which a mid-portion of one of said ribs is snugly received, the prongs of each fork and the portion of the rib received therebetween having relatively small alignable apertures, and a flexible cord strung through the apertures in said rib mid-portions and the ends of said forks to form pivoted joints with said cord of such relative diameter as to be frictionally engaged in those apertures to prevent any appreciable relative separation between parts at said joints, said last-mentioned cord having its ends fastened together to form a loose loop of such dimensions that the lengths thereof between said joints are substantially as long as the width from joint to successive joint of webbing to be mounted on 15 said ribs.

2. In a frame structure for an economical umbrella rib and stretcher arm joint structure comprising, in combination, a plurality of wooden ribs each having a transverse aperture extending through a mid-portion thereof, a plurality of wooden stretcher arms each having one end thereof split to form a fork having a pair of resilient prongs snugly receiving therebetween the aper- 20

tured mid-portion of one of said ribs with said prongs having transverse apertures therein substantially aligned with the aperture in said rib, and a flexible cord strung through the apertures in said rib mid-portions and the ends of said forks to form pivoted joints with said cord of such relative diameter as to be frictionally engaged in those apertures to prevent any appreciable relative separation between the joint parts, said cord having its ends tied together to form a loose loop of such dimensions that the cord lengths between the successive joints will be drawn taut with spread of said ribs by lift of said stretcher arms to umbrella-open positions.
